UNITED STATES PATENT OFFICE

WILLIAM EYRE GADD, OF GLEN OLDEN, PENNSYLVANIA

FIELD TEMPLATE FOR RAILS AND JOINTS

Application filed March 30, 1929. Serial No. 351,224.

This invention relates to rail gauges, and more particularly to a gauge of the adjustable type.

Heretofore, in determining the wear on railway rails, for ascertaining the remaining life of the rail as well as for effecting joint bar renewals or replacements, it has been the customary practice to measure the wear on the surface of the rail head as well as on the fishing surfaces by the use of templates corresponding to the normal rail section. This means of determining wear, however, necessitates the use of a plurality of templates for different size rails and aside from the inconvenience of requiring the carrying of a number of templates for various rail sections, may not always be relied upon for accuracy because of the permissible variations in standard rails due to rolling mill practices. The accurate determination of wear particularly at the joint locations is necessary to permit of either shimming the worn joint bars, or the use of a reformed bar or a new bar that will compensate for the worn-away metal.

A primary object of the invention is therefore to provide a gauge having features of construction whereby the various parts thereof may be adjusted to conveniently and expeditiously compare the rail section at a point or location away from the joint with the rail section at the joint location, after the joint bars have been removed, so as to determine the amount of wear which has taken place where the joint bars have been in service, and also the wear on the surface of the rail head as compared with the normal section.

In that connection the invention also contemplates a template which may be used for comparing one rail or a joint bar with another like section of rail or joint bar.

A further object of the invention is to provide an adjustable gauge construction which permits of the application of the gauge to a wide variety of rail sections thereby eliminating the disadvantages of using several gauges or a plurality of templates for determining wear.

With the above and other objects in view which will more readily appear as the nature of the invention is better understood, the same

consists in the novel construction, combination and arrangement of parts hereinafter more fully described, illustrated and claimed.

A preferred and practical embodiment of the invention is shown in the accompanying drawings, in which:

Figure 1 is a perspective view of the improved gauge illustrating its application to a rail, at a point for example, relatively remote or away from the location of the joint bars.

Figure 2 is an elevation of the improved adjustable rail gauge applied to the rail at a point where the joint bars have been located.

Figure 3 is a side elevation of the gauge shown in Figure 2.

Figure 4 is a detail sectional view taken on the line 4—4 of Figure 2.

Figure 5 is a horizontal sectional view taken on the line 5—5 of Figure 1.

Figure 6 illustrates a modification of the invention showing the template set to check headfree rails.

Figure 7 is a view showing the template set to measure the head wear of a rail.

Figure 8 is a view illustrating the template set to check fishing of head contact joint bars.

Figure 9 is a view showing the template set to check the fishing of a headfree joint bar.

Similar reference characters designate corresponding parts throughout the several figures of the drawings.

In carrying the invention into effect, it is intended to provide a structure which permits of readily making a comparison between the rail as originally rolled and the same rail where it has become worn by frictional contact with the joint bars. By providing a gauge which permits of following this practice, the error incident to comparing the worn fishing surfaces with a template of the rail section is eliminated, since the particular rail in question may vary somewhat, in accordance with the well known practice.

Referring to the drawings, it will be observed that the structure includes a support designated generally as A for engaging the base of the rail, the said support having at one side thereof a vertically arranged carrier

bar B upon which a plurality of gauge arms C, D and E are adjustably mounted.

The support A preferably consists of a body 1 having at one end thereof the slide-
5 able clamping member or clip 2 which may be fixed in any desired position by the set screw 3 or its equivalent after it has been adjusted longitudinally on the member 1 to hold the latter in proper contact with the bottom of the base of the rail. The opposite end of the member 1 is preferably provided with a guideway or recess 4 for receiving the lower end of the carrier bar B which may be held therein by the clamping screw 5. The
10 carrier arm B may therefore be rigidly held at right-angles to the member 1 of the base so that its lower end will act as an abutment against which the clamp 2 may work to hold the entire gauge in position to permit of making the settings or adjustments of the gauge
15 arms at the desired locations on the rail.

The carrier bar B is preferably slotted as indicated at 6 and 7, thereby to receive the clamping bolts 8, 9 and 10 respectively of the adjustable gauge arms C, D and E. The gauge arms C and D are preferably of tapering formation and are slotted as indicated at C' and D' to permit of longitudinal adjustment into and out of the fishing space of the
25 rails, as well as angular adjustment. Thus, the gauge arms C and D are adjustable both vertically and horizontally to thereby accurately contact with the inclined fishing surfaces of the rail.

30 The upper gauge arm E is provided with a guide slot 11 for receiving the upper end of the carrier bar B so that upon the loosening of the clamping bolt 10 the arm E may only have a vertical movement since it contacts with the surface of the rail and is used for measuring the height of the rail from its base to its surface.

In use, the supporting portion or bracket A is fitted to the base of the rail as a location
45 away from the joint bars as shown in Fig. 1, by moving the adjustable clamp 2 over the base flange of the rail and pulling the carrier arm B into abutting relation with the edge of the opposite base flange. The clamp 2 is then fixed in position by tightening the set screw 3 and the gauge arms C, D and E are then ready for manipulation to make the desired contact and measurements. In that connection the upper gauge arm E may be
50 brought into contact with the surface of the rail and then the adjustable arms D and E are clamped against the underside of the rail base and the underside of the rail head respectively. In this way a template is obtained of the rail fishing at a location where
55 there has been no wear. A joint bar is then removed and the template is applied to the rail where the bar had been. This is done by removing the clamping member 2 and
60 replacing it after the gauge has been applied

to its new location and again fixed in position by re-applying the clamp 2 over the end of the member 1 and fitting it to the rail base.

The amount that the rail has been worn in the fishing is then determined by inserting a thickness gauge between the underside of the arm C and the underside of the rail base flange and between the upper edge of the arm D and the underside of the rail head.

If the top surface of the rail head is worn more at the joint than where the gauge was originally set on the rail, this can also be determined by inserting a thickness gauge between the underside of the arm E and the top of the rail head.

The gauge can also be used in determining approximately the amount of wear on the upper surface of the rail head by setting the arm E to the height of the full rail section and then obtaining a contour of the worn head.

From the foregoing it will be apparent that the present construction provides an adjustable track gauge which has advantages over a regular rail template in that it is set to fit the fishing of the particular rail in question and then ascertaining, by applying the gauge to the rail end where the joint has been applied, the amount of wear. While in one of its modified forms of uses the adjustable gauge permits of obtaining the contour of the rail head, its chief object is to provide a gauge which enables of making a direct comparison in the field between the worn rail in track and a section of the worn rail, so as to determine the amount of rail wear in the fishing at the rail ends where the joint bars have been in contact.

Figures 6, 7, 8 and 9 of the drawings illustrate the application of the invention to a wide range of uses.

Referring to Figure 6, it will be observed that the gauge or template may be used to check headfree rails. According to the arrangement shown, the template for this purpose includes the supporting member A for engaging the rail base and the top gauge arm E as well as the previously described gauge arm C for engaging with the upper side of the rail flange. However, to adapt the template to test a headfree rail additional gauge elements D² and D³ may be adjustably secured to the carrier arm B. These gauge arms D² and D³ are provided with special gauge surfaces or edges for accomplishing the purpose set forth. For instance, the gauge member D² is provided with the rounded nose portion 12 for engaging with the head fillet of the headfree rail while its opposite end has one corner formed with an arcuate cut away portion or notch 13 adapted to be used in checking the fishing of headfree joint bars as will be seen from Figure 9. The gauge member D³ is formed at one end with a flat end portion 14 arranged at an angle

to contact with the flat surface of the lower portion of the rail head. The opposite end of the member D^3 is formed with a rounded or substantially semi-circular gauge surface 5 15 to be used in checking the fishing of the joint bars as will be apparent from an examination of Figures 8 and 9.

In connection with the gauge members D^2 and D^3 , it will, of course, be understood that 10 the same are provided with suitable adjustment slots 16 and 17 for receiving the wing bolts or equivalent fastenings 18 and 19 which ride in the slot 7 of the carrier bar B and permit of securing the gauge members 15 D^2 and D^3 at the desired location for checking purposes.

From the foregoing it will be apparent that 20 by utilizing gauge members of suitable shape and design the present device may be applied to various uses and is of greatest value in the field for the purpose of determining the amount of wear that has taken place on the section of a rail or joint bar by comparison, and for comparing one side of the rail with 25 the other side.

By way of further explaining the manner of using the template, it may be observed from Figure 6, in which the device is set for 30 checking a headfree rail, that the supporting member A may be applied to the base of the rail and the top gauge member E applied to the rail surface, while the gauge member C, D^2 and D^3 may be adjusted vertically and 35 horizontally to fit any rail section from 85# to 136# inclusive. To compare the fishing of the rails, the supporting member A and carrier arm B are made to fit tight against the bottom and outer edge of the rail flange, and the clip 2 is secured on the supporting 40 member 1 to hold the entire device in position. The lower gauge member C may then be adjusted so that it rests evenly on the flat portion of the upper side of the rail base, and then the intermediate gauge member D^2 may 45 be adjusted so that the mid-points of the radius of the fillet on the rail head and the radius of the end 12 approximately coincide. The member D^2 may then be secured or set in 50 position and then the upper gauge member D^3 may be adjusted so that the edge 14 rests evenly on the flat portion of the rail head. When all of the gauge members have been 55 set to the proper position the clip 2 may be removed from the supporting member 1 and the template is then ready for removal and application to another rail. When applied to the other rail by means of the clip 2, by use of thickness gauges the clearance between 60 the adjustable members of the template and the rail may be measured. If the template does not fit tight with the carrier bar B against the edge of the rail base, the template should be set to the latter rail and then replaced on the former rail as this condition in-

dicates that the former rail is worn more than the latter rail.

Referring to Figure 7, the template is secured to the rail in the manner heretofore described until the top gauge member E 70 touches the top of the rail. The template is then removed and the distance from the lower edge of E to the top edge of A is measured. This measurement subtracted from the height of the rail will show the amount of 75 wear. If desired, the template can be secured to another rail and the difference in amount of wear measured by a thickness gauge. No attempt is made to check curve or flange wear with this template. It is only used to determine the amount of head wear, principally for use in connection with applying new joint bars on worn rails where the head wear is a governing feature inasmuch as the rail is unfit for further use if worn so badly that 80 it will permit the wheel flanges to strike the tops of the joint bars.

Figure 8 of the drawings shows the assembly of parts set to check fishing of head contact joint bars. The gauge members C, 90 D^2 and D^3 are adjusted on the carrier bar B to fit the fishing surfaces at the head and foot of the bar, the intermediate gauge member D^2 engaging the inside face of the bar to provide a third point of contact to insure a closer 95 check. When the template thus assembled has been set to one joint bar, it may be removed and applied to another joint bar and measurements taken with a thickness gauge.

In Figure 9 the template is shown with 100 the gauge members adapted to check the fishing of headfree joint bars. The lower gauge member C is set to engage the lower bottom fishing surface of the bar while the top gauge member D^2 has the arcuate portion 13 adjusted so that the approximate mid-point of the head radius of the joint bar coincides with the mid-point 13^a of the radius on which the notch is struck. Also to give a third point of contact, and to insure a closer check the gauge member D^3 is set so that the rounded edge 15 engages with the lower side of the 105 head of the bar.

Without further description it is thought 110 that the features and advantages of the invention will be readily apparent to those skilled in the art and it will of course be understood that changes in form, proportion and minor details of construction may be resorted to without departing from the spirit 115 of the invention and scope of the appended claims.

I claim:

1. A field gauge for rails and joints including a support comprising a member for engaging with the underside of the rail base, a rail flange engaging clamp slidably mounted on one end of said member, means for locking said clamp to the member to fasten the gauge to the rail base, an upright carrier 125 130

bar secured to the end of the rail base engaging member opposite the clamp, a plurality of rail surface engaging gauge arms, and means mounting said gauge arms on said carrier bar for adjustment longitudinally therealong and also transversely and pivotally relative thereto.

2. A rail gauge comprising a member adapted to be disposed against the bottom face of a rail, an upright carried by said member and constituting an abutment for contact with one edge of the rail flange, a clamp element carried by said member for engagement with an opposite side portion of the rail flange to secure said member to the rail with said upright abutting the edge of the rail flange, a plurality of gauge elements and means mounting said gauge elements on said upright for longitudinal, transverse and pivotal adjustments relative thereto, one of said gauge elements being disposed for gauging engagement with the upper face of the adjacent side portion of the rail flange and for cooperation with the clamp element to secure the gauge to the rail.

3. A rail gauge comprising a member adapted to be disposed against the bottom face of a rail, an upright carried by said member, means for securing said member against the bottom face of a rail with the upright disposed in a predetermined definite position relative to the side of the rail, rail gauge elements, and means mounting said rail gauge elements on said upright for longitudinal adjustments therealong and for pivotal adjustments relative thereto.

In testimony whereof I hereunto affix my signature.

WILLIAM EYRE GADD.
